(57) **CLAIM**

The ornamental design for a gas cap container lid, as shown and described.

DESCRIPTION

FIG. 1 is a top front perspective view of a gas cap container lid in accordance with the present invention, shown in a position of use on a container in broken lines;

FIG. 2 is a top front perspective view of the gas cap container lid of FIG. 1, shown removed from the container;
FIG. 3 is a front view of the gas cap container lid of FIG. 2;
FIG. 4 is a side view of the gas cap container lid of FIG. 2;
FIG. 5 is a top view of the gas cap container lid of FIG. 2; and,

FIG. 6 is a bottom view of the gas cap container lid of FIG. 2.

The broken lines illustrating a container depict environmental subject matter and form no part of the claimed design. All other broken lines depict portions of the gas cap container lid that form no part of the claimed design.
